(57) **CLAIM**

The ornamental design for a “solar powered light”, as shown and described.

DESCRIPTION

FIG. 1 is a front view of a “solar powered light” showing my design;

FIG. 2 is a right side view thereof, the left side being a mirror image;

FIG. 3 is a top plan view thereof; and,

FIG. 4 is a perspective view thereof.

The light bulb shown in broken lines is for illustrative purposes only, and forms no part of the claimed design.
